UNITED STATES PATENT OFFICE.

THOMAS R. FARLEY, OF DES MOINES, IOWA.

DESIGN FOR A FLAG, PENNANT, SIGN, EMBLEM, OR ARTICLE OF A SIMILAR NATURE.

54,537.

Specification for Design.

Patented Mar. 2, 1920.

Application filed January 17, 1919. Serial No. 271,752. Term of patent 3½ years.

To all whom it may concern:

Be it known that I, THOMAS R. FARLEY, a citizen of the United States, and resident of Des Moines, Polk county, Iowa, have invented a new, original, and ornamental Design for a Flag, Pennant, Sign, Emblem, or Article of a Similar Nature, of which the following is a specification, reference being had to the accompanying drawing, forming part thereof.

The figure is a plan view of a flag showing my new design, the same consisting of a center white body, a blue star in the center thereof and a border formed of stripes of various colors which represents the colors of the allies and in the center white space above the star is the word "Honorable" and below the star is the word "Discharged."

I claim—

The ornamental design for a flag, pennant, sign, emblem, or article of a similar nature as shown and described.

In testimony whereof, I have signed my name to this specification, in presence of two subscribing witnesses.

THOMAS R. FARLEY.
